PLEATED MATERIAL AND METHOD OF
MAKING THE SAME

Paul Tutein, deceased, late of Copenhagen, Denmark, by Kamma Tutein, widow, Copenhagen, Denmark

Application April 14, 1938, Serial No. 202,020
In Germany September 9, 1937

13 Claims. (Cl. 93—84)

This invention relates to folded or pleated material, and is concerned more particularly with such materials in which the folds are of novel arrangement, so that the materials may be used in making articles and bodies for various purposes. The invention further includes a novel method by which the new products may be made of such materials as paper, cardboard, metal foil, sheet metal, etc.

10 According to the methods of pleating commonly employed heretofore, the sheet material is folded first in one way and then the other along a series of straight, generally parallel lines, so that the material may be expanded and compressed or bent on axes parallel to the lines of folding. Material pleated in this manner may be folded or bent on axes parallel to the lines of folding, but cannot be so manipulated on other axes without distorting the pleats and thereby stiffening the material against the desired expansion and compression. As a result, the material may be used for a relatively few objects, in each of which the surface of the material is straight in the direction of the pleats, and the use of the material is thus restricted to a few uses.

15 The present invention is directed to the provision of a novel method of pleating by the practice of which a material may be readily made which is suitable for use in the formation of articles and bodies which cannot be made of material pleated or folded by prior methods. In accordance with the new method, the material is folded on three systems of straight intersecting lines so arranged that members of all systems intersect at the same points, the material thus being subdivided by lines of folding into parallelograms, each having a line of folding as one diagonal. The folding on the diagonals is in the same direction throughout the sheet, and the folding on the lines in the other two systems is likewise in the same direction, but inversely to the folding on the diagonals. If desired, the three systems of lines may be so arranged that the parallelograms have the form of rhombs, in which case the diagonals are lines of symmetry for the other two systems of lines, and the entire system of folding can be characterized as symmetrical. In order that a complete compression of the material thus folded may be made freely, it is desirable that the diagonal lines extend through the acute angles of the parallelograms, so that the diagonals in symmetrical systems divide the acute angles of the parallelograms into equal angles of less than 45°.

20 In materials folded in the manner described, the two portions of each parallelogram lying on opposite sides of its diagonal extend outwardly from the diagonal, and the sides of the parallelograms are defined by folded edges of the compressed material arranged angularly relative to one another, the number of such edges in a piece of the material depending on the number of parallelograms lying end to end lengthwise of a diagonal. By appropriate manipulation of the folded material, it may be formed into various articles, as, for example, by partly drawing out the material, a facet, trough-shaped body may be formed which can be inscribed in a cylindrical surface, and by turning one end of the material about an axis, bodies may be formed which can be inscribed in other surfaces of revolution. Also, a variation of the forms thus obtained may be had by omitting the folding along part of the diagonal lines within certain of the parallelograms or along part of the sides of the parallelograms, or both.

25 The method of the invention is particularly suited to the manufacture of tubes of large surface area, which may be drawn out and compressed axially in the manner of a bellows. In forming tubes in this way, a sheet of material of the appropriate width is folded to form staggered rows of parallelograms extending end to end transversely of the sheet, the parallelograms in each row being in such number and so proportioned that the pleated material when compressed forms a polygon having a periphery which is continuous except for a break at adjacent edges of the sheet. When the material is expanded and the edges are suitably joined, the material forms a tube of large surface area. If desired, the opposite procedure may be followed, namely, a tube may have folds made in its wall along the appropriate lines to produce the same result. Tubes thus formed, even when made of sheet metal, are flexible in all directions so that they are suitable for a variety of purposes where flexibility or resilience is desirable. Also, the large surface in relation to the volume makes such a tube useful for heat transmission.

30 For a better understanding of the invention, reference may be had to the accompanying drawing, illustrating different forms of the invention in which the folds are made on symmetrical systems of intersecting lines. It will be understood, however, that the forms shown are merely for the purpose of illustration and that the folds may be made as well on an unsymmetrical system of lines, that is, on a system

of lines forming parallelograms which are not equilateral. In the drawing:

Fig. 1 is a plan view of a sheet of the new pleated material drawn out, the width of the sheet being half the length of the diagonal of a rhomb which would be formed by extending the three systems of intersecting lines;

Fig. 1a is an end view of the sheet shown in Fig. 1, in compressed form;

Fig. 1b is a plan view of the sheet shown in Figs. 1 and 1a, partly drawn out;

Figs. 2, 2a and 2b are views similar to those of Figs. 1, 1a and 1b, respectively, but showing a sheet of pleated material of a width equal to the diagonal of the rhombs;

Fig. 3 is a plan view of another sheet of pleated material partly broken away and drawn out, the width of the sheet in this instance being twice the length of the diagonal of the rhombs;

Fig. 3a is an end view of the sheet shown in Fig. 3, in compressed form;

Figs. 3b and 3c are side and end views, respectively, of two articles made from the sheet shown in Fig. 3;

Fig. 4 is a plan view of another pleated sheet of a width equal to three times the length of the diagonal of the rhombs;

Fig. 4a is an end view of the sheet shown in Fig. 4, in compressed form, and

Fig. 4b is a side view of the compressed material shown in Fig. 4a partly drawn out and shaped to the form of a tube.

A simple method of pleating embodying the principles of the invention is illustrated in Fig. 1 which shows a sheet of material folded in one direction along a system of spaced parallel transverse lines 10, and in the opposite direction along a system of parallel oblique lines 11 and another system of parallel oblique lines 12, the two systems of oblique lines 11 and 12 being so disposed as to form alternately inverted and upright isosceles triangles 13 of a height equal to the width of the sheet and bisected by the system of lines 10. Each such triangle 13 is in effect one half of a rhomb which would be formed by extending the systems of lines, the width of the sheet being half the length of the diagonal of such a rhomb. When the sheet is compressed on the folds, the oblique fold lines 11 and 12 lie in a common plane 14 (Fig. 1a), while the fold lines bisecting the inverted isosceles triangles 13 lie in a common plane 10a and those bisecting the upright triangles lie in a common plane 10b. By partly drawing out the compressed sheet of material, the sheet shown in Fig. 1b is obtained, the sheet being made up of a plurality of flat, right triangular areas, each inclined relative to the adjacent areas.

In order to pleat the material so that it is bent in the direction of the pleats, it is prepared in the manner shown in Fig. 2 by folding it in one direction along a system of spaced parallel transverse lines 15, and in the opposite direction along a system of parallel oblique lines 16 and another system of parallel oblique lines 17. The oblique lines 16 and 17 intersect to form a row of rhombs 18, each bisected by one of the vertical lines 15 forming a diagonal of a length equal to the width of the sheet, and the portions of the sheet between adjacent rhombs are in the form of opposed isosceles triangles 19 having their bases at the top and bottom edges of the sheet, respectively. When the folded sheet is compressed (Fig. 2a), the diagonals or alternate transverse folds 15 lie in a common plane and the

two halves of each rhomb 18 are bent back on each other, while the two halves into which the triangles 19 are divided by the vertical folds 15 are doubled back on the adjacent side areas of the rhombs and form gussets between the rhombs. By partly drawing out the compressed sheet, the trough-shaped article shown in Fig. 2b is obtained.

The depth of the trough-shaped article shown in Fig. 2b is dependent on the angular relation of the folds 16 and 17 forming the sides of the rhombs, and the depth may be increased by increasing the inclination of the oblique lines 16 and 17 with respect to the vertical lines 15, and vice versa. Also, while the pleated sheet is shown in the form of a trough, it may be manipulated into various other articles, as will be apparent from the following description of a somewhat similar pleated sheet shown in Fig. 3.

This sheet illustrated in Fig. 3 is pleated in a manner similar to that shown in Fig. 2, except that the system of transverse lines 20 and the two systems of intersecting oblique lines 21 and 22, respectively, form rhombs 23 having diagonals of a length equal to one half the width of the sheet. Accordingly, the sheet is divided into upper, intermediate and lower rows of rhombs extending in staggered relation across the sheet, and a plurality of isosceles triangles 24 between adjacent rhombs in the upper and lower rows. When the sheet is compressed on the folds, it assumes the form shown in Fig. 3a wherein the diagonal folds of the upper row of rhombs lie in a common plane 25, and those of the rhombs in the intermediate and lower rows lie in common planes 26 and 27, respectively. The two parts into which each rhomb is divided by its diagonal fold are bent back on each other, while the parts into which the triangles 24 are divided by their median folds 28 are doubled back on the adjacent areas of the rhombs.

By appropriate manipulation of the sheet shown in Fig. 3a, it may be formed into various articles, as, for example, by partly drawing it out, it will assume a trough-shaped form which is faceted and may be inscribed in a cylindrical surface. Also, the sheet may be made into the hollow faceted body shown in Fig. 3b by turning one end thereof through 360° about the axis A—A, the body thus formed being inscribable in a surface of revolution. It will be understood that by turning the end through less than 360° about the axis A—A a faceted cup-shaped body is formed, and that by turning the end in the opposite direction, that is, about the axis B—B, a faceted body of different form may be produced. The body shown in Fig. 3c may be formed by turning the end of the sheet through 180° about the axis C—C which is inclined to the axes A—A and B—B. These and other forms made from the sheet shown in Fig. 3 may be used for a number of purposes, such, for example, as decorations, lamp shades, and the like.

In the manufacture of tubes according to my invention, a sheet of suitable material, such as a fibrous material, metal, or the like, is folded in one direction along the system of transverse lines 29 and in the opposite direction along the two systems of oblique intersecting lines 29 and 30, the lines being so spaced as to form rhombs 31 having diagonal folds of a length equal to one-third or a smaller fraction of the width of the sheet. In Fig. 4, the diagonals of the rhombs are of a length equal to one-third of the width of the sheet, so that the rhombs are disposed in five

staggered, horizontal rows designated 31, 32, 33, 34 and 35, respectively, the portions of the sheet between adjacent rhombs in the outer rows 31 and 35 being in the form of isosceles triangles 36 which serve as gussets between the adjacent sides of the rhombs.

When the sheet is compressed, it assumes the form shown in Fig. 4a wherein the diagonal folds in the rows 31 to 35, inclusive, lie in common planes 31' to 35', inclusive, respectively, and the two parts of each rhomb on opposite sides of its diagonal are bent back and outwardly on each other so that the sides of all of the rhombs together form an equilateral hexagon. The triangular areas 36 at the edges of the sheet are doubled back on their median folds 28 so that they lie against the adjacent areas of the rhombs in the outer rows 31 and 35, whereby the median folds of the triangles lie in a common plane 36', with the bases of the triangles meeting in a plane 37. Accordingly, by making a continuous joint between the bases of the opposing triangles 36, that is, between the top and bottom edges of the sheet in the plane 37, a body is formed which is completely closed, except at its ends, and by drawing the body partly out, the faceted pipe shown in Fig. 4b is obtained.

The number of sides of the polygon shown in Fig. 4a is equal to twice the number of rhombs which extend end to end in a row across the sheet, and, accordingly, for every unit increase in the latter number, the number of sides of the polygon is increased by two. Also, in order to form a regular polygon by compressing the sheet, it is necessary that the angle y between the oblique lines and the transverse lines 28 satisfy the equations

$$n = \frac{360}{2y}$$

and

$$b = \frac{n \cdot b}{\tan y}$$

where n is the number of sides of the polygon or twice the number of rhombs extending end to end in a transverse row on the flat sheet, b the width of the flat sheet, and a the distance between adjacent vertical folds 28. Accordingly, for the hexagonal tube illustrated, the angle y must be 30° .

While the compressed sheet of Fig. 4a is shown drawn out into a tube, it will be understood that it may be formed into other bodies by appropriate manipulations, as, for example, by turning 5 the ends thereof about a suitable axis.

The method of the invention may also be employed to transform an ordinary smooth surfaced tube into a pleated one by making a plurality of folds extending circumferentially around the cylindrical surface of the pipe, as for example, the folds may be made by pinching the pipe from the inside. The circumferential folds are the equivalent of the vertical folds 28 and may be spaced accordingly. The surface of the pipe is also folded by pinching it from the outside along two systems of intersecting lines equivalent to the lines 28 and 30 and extending in continuous, equidistant helical lines so arranged as to satisfy the equation $a \cdot h = n \cdot d \tan y$, where a is the distance between adjacent circumferential folds, h the number of sides desired in the polygon forming the base of the pleated tube, d the diameter of the cylindrical tube, and y the angle between the helical and circumferential folds.

The tube may then be compressed into a pleated form similar to that shown in Fig. 4b.

It will be apparent that by the practice of my new method, materials of any suitable kind, such as fibrous materials, metal, and the like, may be readily pleated and manipulated into the desired forms, and since articles made in this manner have a relatively large surface per unit of projected area, they may be used to advantage for numerous purposes.

What is claimed is:

1. A pleated sheet having folds extending in spaced, substantially parallel planes, the fold in each of at least alternate planes being formed of two parts disposed in angular relation.

2. A pleated sheet folded along three systems of intersecting lines, the sheet being divided by lines of folding into parallelograms each with one diagonal.

3. A pleated sheet folded along three systems of intersecting lines, the sheet being divided by lines of folding into rhombs each with one diagonal.

4. A pleated sheet folded along three systems of intersecting lines, the sheet being divided by lines of folding into parallelograms each with one diagonal, the diagonals being folded in a direction opposite to the direction of the folds forming the sides of the parallelograms.

5. A hollow body having a surface inscribable in a surface of revolution and folded along three systems of intersecting lines, the surface of the body being divided by the lines of folding into parallelograms each with one diagonal, and the lines of folding forming angularly disposed pleats extending in planes substantially parallel to the axis of said surface of revolution.

6. A tube having its surface folded along three systems of substantially straight, intersecting lines, one system of lines extending around the tube in spaced, parallel planes perpendicular to the tube axis, and the other two systems extending obliquely to the first system and dividing the surface into parallelograms wherein the lines of said first system form diagonals, the tube being compressible in a direction perpendicular to the diagonals.

7. A method of pleating sheet material which comprises folding the sheet in one direction along a system of substantially parallel lines, and folding the sheet in the opposite direction along a system of substantially parallel lines oblique to the lines of the first system and along another system of substantially parallel lines lying at an angle to the lines of the first two systems, the lines of the three systems intersecting at common points and dividing the sheet into parallelograms each with one diagonal.

8. A method of making pleated tubes which comprises folding sheet material in one direction along a system of substantially parallel lines, and in the opposite direction along two systems of intersecting lines dividing the sheet into parallelograms in which the first system of lines forms diagonals, the lines being disposed to form rows of at least three parallelograms extending transversely across the sheet, compressing the sheet on the folds in a direction transverse to the diagonals, and joining the adjacent edges of the sheet.

9. A method of pleating tubes which comprises forming a plurality of pleats extending circumferentially around a tube and in spaced relation, folding the tube along a system of substantially parallel, continuous, helical lines extending

around the tube and along another system of substantially parallel, continuous, helical lines at an angle to the helical lines first mentioned, the lines of the systems intersecting at common points, whereby the surface of the tube is divided by lines of folding into a plurality of parallelograms each with one diagonal, and compressing the tube axially on the folds.

10. A trough-shaped article comprising a flexible sheet folded along three systems of intersecting lines, the sheet being divided by the lines of folding into parallelograms each with one diagonal extending generally transversely of the article, and the sheet being collapsible along said lines of folding.

11. A tube having its wall folded along three systems of intersecting lines, the wall being divided by the lines of folding into parallelograms each with one diagonal substantially perpendicular to the axis of the tube.

12. A method of making pleated articles which comprises folding sheet material in one direction along a system of substantially parallel lines and in the opposite direction along a system of substantially parallel lines oblique to the lines

of the first system and along another system of substantially parallel lines lying at an angle to the lines of the first two systems, the lines of the three systems intersecting at common points and dividing the sheet into parallelograms each with one diagonal, compressing the material in a direction transverse to the diagonals, and partly drawing out the compressed material.

13. A method of making pleated articles which comprises folding sheet material in one direction along a system of substantially parallel lines and in the opposite direction along a system of substantially parallel lines oblique to the lines of the first system and along another system of substantially parallel lines lying at an angle to the lines of the first two systems, the lines of the three systems intersecting at common points and dividing the sheet into parallelograms each with one diagonal, compressing the material on the folds in a direction perpendicular to the diagonals, and turning one end of the compressed material about an axis.
